UNITED STATES PATENT OFFICE.

HOMER L. ENNES, OF SANDUSKY, OHIO.

DESIGN FOR A FENCE-POST STUB.

SPECIFICATION forming part of Design No. 20,137, dated September 9, 1890.

Application filed August 9, 1890. Serial No. 361,591. Term of patent 7 years.

To all whom it may concern:

Be it known that I, HOMER L. ENNES, a citizen of the United States, and a resident of Sandusky, in the county of Erie and State of Ohio, have invented certain new and useful Improvements in Fence-Post Stubs; and I do declare the following to be a full, clear, and exact description of the invention, such as will enable others skilled in the art to which it applies to make and use the same, reference being had to the accompanying drawings, and to letters of reference marked thereon, which form a part of this specification.

Figure 1 of the drawings is a side elevation. Fig. 2 is a top plan view.

This invention has relation to designs for fence-post stubs; and it consists in a novel form and configuration of the parts thereof, as hereinafter shown and described.

In the accompanying drawings, illustrating the design, the letter A indicates the base of the stub, which extends horizontally from the column portion B, forming a broad bottom

flange, as shown. The column portion B consists of the opposite parts C and C, which are connected by a partition D. Between the parts C and C, on each side of the partition D, is a dovetail channel or seat E, which extends vertically, as shown. Through the partition D are the bolt-openings F F, centrally arranged in series, as shown.

What I claim, and desire to secure by Letters Patent, is—

The design for fence-post stubs, consisting of the base portion A, and rising therefrom the column B, consisting of two portions connected by a partition and having the dovetail channel E on each side of said partition, as shown and set forth.

In testimony whereof I affix my signature in presence of two witnesses.

HOMER L. ENNES.
